UNITED STATES PATENT OFFICE

2,480,335

AUTOMATIC REEL

Walter E. Nordmark, Grand Rapids, Mich., assignor to American Seating Company, Grand Rapids, Mich., a corporation of New Jersey

Application April 9, 1945, Serial No. 587,411

14 Claims. (Cl. 155—189)

1

The present invention relates to automatic reels, and more particularly to an automatic reel for taking up a cable attached to a shoulder harness by means of which an occupant of an airplane or other vehicle is secured in his chair.

The primary objects of the invention are to provide a novel automatic reel for reeling in a shoulder harness cable whenever tension on the cable is relaxed, and for paying out the cable as necessary to permit freedom of movement to the 10 chair occupant whenever such freedom of movement is both desirable and safe; to provide such an automatic reel having inertia-actuated parts for positively securing the cable against paying out during collisions, crash-landings or other emergencies, thus to prevent the chair occupant from being thrown forward against the instrument panel, windshield or other appurtenance of the vehicle and sustaining serious or fatal injuries; to provide selective means whereby the 20 chair occupant may adjust the reel either to permit freedom of movement by him (except as such movement might be prevented by the aforesaid inertia-actuated parts) or to positively prevent such movement as may be found desirable in upside-down flying, emerging from power dives, or other maneuvers; and in general to provide such an automatic reel which is simple in construction, efficient in operation, and reasonably economical in manufacture.

These objects are attained by the illustrative embodiment of the invention shown in the accompanying drawings, wherein:

Figure 1 is a side and rear perspective view of an airplane pilot chair showing the chair occupant and shoulder harness in rearward position in full lines and in forwardly drawn position in dotted lines, and showing the automatic reel and selective control mechanism therefor attached to the chair;

Figure 2 is a full scale rear elevational view of the automatic reel with a portion of the housing broken away to disclose parts on the interior thereof;

Figure 3 is a sectional view of the same taken on line 3—3 of Figure 2;

Figure 4 is a fragmentary sectional view thereof taken on line 4—4 of Figure 3;

Figure 5 is a left hand side elevational view of the automatic reel with a portion of the housing broken away to disclose parts on the interior thereof;

Figure 6 is a perspective view of a spring unit for the automatic reel;

Figure 7 is a full scale side elevational view of selective control mechanism for the reel;

Figure 8 is a sectional view of the same taken on line 8—8 of Figure 7; and

Figure 9 is a fragmentary sectional view thereof taken on line 9—9 of Figure 8.

2

Referring now in detail to these drawings wherein each part is designated by the same numeral in the several views, the pilot chair 1 is provided with fittings 2 by means of which the chair is mounted upon a frame 3 adapted to be secured by any suitable means (not shown) in an upright position at the pilot's station in an airplane. The chair is equipped with a conventional safety belt 4 extending from side to side thereof and secured thereto by means of conventional fittings 5.

The automatic reel generally designated 6 has a base 7 secured by means of bolts 8 and nuts 9 to the lower back of the chair 1. A centrally located, rearwardly projecting spindle 10 is provided with a forward flange 11 thereon seated in a recess 12 in the base 7 and rigidly secured thereto by rivets 98.

A drum generally designated 13 is rotatably and longitudinally slidably mounted on the spindle 10. This drum has in its rearward portion a concentric annular recess 14 in which is disposed a coil tension spring 15 whose inner end 16 is seated in a kerf 17 in the spindle 10 and whose outer end 18 is seated in a slot 19 in the drum 13. A cover 20 is pressed into the recess 14 for retaining the coil spring therein. This coil spring 15 tends to rotate the drum 13 in a counter-clockwise direction as viewed from the rear.

An eccentric well 21 extends forwardly from the recess 14 in the drum 13, and this well 21 accommodates a cable-tip 22 secured to one end of a cable 23, the other end of which cable 23 is provided with a clevis 24 secured by a pin 25 to the rearward lower end of a shoulder harness 26 whose forked shoulder straps 27 extend over a cross-bar 28 on the frame 3 and over the respective shoulders of the chair occupant. The forward lower ends of the shoulder straps 27 are secured in any suitable manner to the safety belt 4.

The drum 13 of the reel 6 has a peripheral groove 29 communicating with the eccentric well 21 and of sufficient depth to accommodate several turns of the cable 23. It will be seen that the action of the coil spring 15 tends to wind the cable 23 onto the drum 13 whenever tension on the shoulder harness 26 is relaxed.

A circular boss 30 on the forward surface of the drum 13 is provided with ratchet teeth 31 adapted to interlock with complementary ratchet teeth 32 on a circular boss 33 on the rearward surface of the base 7. These ratchet teeth 31 and 32 interlock when the drum 13 is slid forwardly on the spindle 10, and such interlocking positively prevents rotation of the drum in a clockwise direction as viewed from the rear, thus to prevent paying out of the cable 23 when the drum is in its forward position.

A novel spring unit for normally urging the drum 13 in a rearwardly direction is best seen

in Figure 6. This spring unit is generally designated 34 and comprises complementary spring leaves 35 identically stamped from sheet metal and each provided with a flange 36 at one end, an aperture 37 at the other end, and a bowed middle portion having a central opening 38 therein. The two spring leaves 35 are assembled in opposite, outwardly bowed juxtaposition with the flange 36 of each leaf engaging in the aperture 31 of the other leaf.

The assembled spring unit 34 is interposed between the drum 13 and the base 7, with the spindle 10 extending through the central openings 38 therein. The spring unit yieldingly urges the drum rearwardly out of interlocking engagement with the base and thus permits freedom of movement to the chair occupant under normal conditions of travel. However, when the movement of the vehicle is abruptly decelerated, as in a collision or other emergency, the inertia of the drum 13 overcomes the rearward pressure of the spring unit 34 and the drum 13 slides forwardly into ratchet engagement with the base 7. In this locked position of the drum, the cable 23 is thus made secure against being drawn outwardly by the forward inertia of the chair occupant, and the occupant is maintained in a safe, rearward position against the chair back.

A cover or housing 39 enclosing the drum 13 and adjacent parts is secured to the assembly by means of a screw 40 passing through a central opening 41 in the housing and threaded in the rearward end of the spindle 10. The housing 39 may also be provided with a flange 42 having apertures 43 through which pass the bolts 8 for additionally securing the housing to the assembly. An opening 44 in the housing permits free travel of the cable 23 therethrough, said opening being preferably shielded by a dust-cover 45 having a case member 46 secured to the housing 39 by rivets 47 and a cover member 48 secured to the case member 46 by means of a cotter 49 passing through aligned apertures 50 in these two members.

Selective mechanism is provided whereby the chair occupant may manually adjust the reel to locked position if he so desires. This mechanism comprises a control lever 51 having a yoke portion 52 within the housing whose inner arms 53 are bent to form lugs 54 which bear against opposite sides of the drum 13 for sliding the drum forwardly against the pressure of the spring unit 34. The control lever 51 extends through, and is fulcrumed in, a slot 55 in the housing 39 and has a forwardly extending outer lever arm 56 which is connected as hereinafter described to a control switch generally designated 57 mounted on the side of the chair 1 and conveniently accessible to the occupant of the chair.

As best shown in Figures 7, 8 and 9, the control switch 57 comprises a mounting plate 58 secured to the pilot chair 1 by means of bolts 59 having nuts 60. A switch barrel 61 has a reduced, cylindrically formed and inwardly turned lower portion 62 journalled in a bearing member 63 secured as by welding in an opening 64 through the mounting plate 58. A switch plunger 65 is slidably disposed in the switch barrel 61 and has a forwardly-rearwardly extending slot 66 through which extends an arcuate guide 67 secured to the chair 1 by means of bolts 68 having spaced collars 69 and provided with nuts 70 on the outer ends thereof.

A compression spring 71 within the switch barrel 61 normally urges the switch plunger 65 up-

wardly so that the bottom of the slot 66 engages the bottom edge of the arcuate guide 67. This guide 67 has a pair of cutouts 72, 73 for releasably maintaining the switch plunger 65 in its forward and rearward positions respectively.

A crank 74 is fixedly secured on the inner end of the lower portion 62 of the switch barrel 61, and has an outwardly turned flange 75 provided with a slot 76 through which extends the forward end of a flexible control cable 77 longitudinally slidably disposed in a flexible control tube 78 whose forward end is secured in the curled upper portion 79 of a bracket 80 fastened by means of a bolt 81 and nut 82 to the mounting plate 58. The bracket 80 is secured against turning by means of a lug 83 engaging in a notch 84 in the mounting plate 58.

The forward end of the flexible control cable 77 is connected to the crank 74 by means of a stop 85 on the forward side of the crank's flange 75, which permits the switch plunger 65 to be moved rearwardly without moving the control cable 77. Forward movement of the switch plunger, however, draws the control cable 77 forwardly.

The rearward end of the flexible control tube 78 is secured in the curled outer portion 86 of a mounting bracket 87 whose base portion 88 is secured by rivets 89 to the housing 39 of the automatic reel 6, and the rearward end of the flexible control cable 77 is connected to a rod 90 slidably mounted in a bearing 91 in the rearwardly extending medial portion 92 of the mounting bracket 87. A compression spring 93 circumscribes the rod 90, its outer end abutting the medial portion 92 of the mounting bracket 87 and its inner end abutting a shoulder 94 on the inner end of the rod 90. A tension spring 95 connects the inner end of the rod 90 with the outer lever arm 56 of the control lever 51.

It will be seen that when the occupant of the chair manually depresses the switch plunger 65 and moves the same forwardly from its full line position shown in Figure 7 to its dotted line position shown in the same view, the control cable 77 is moved forwardly thus moving the rod 90 outwardly and placing additional compression on the spring 93 and additional tension on the spring 95. The spring 95 thus turns the control lever 51 so that the lugs 54 bear against the drum 13, which slides the drum into locking engagement with the base 7 of the automatic reel and further compresses the leaf spring unit 34. This locks the harness cable 23 and shoulder harness 26 thus restraining the chair occupant against forward movement.

When the occupant of the chair depresses the switch plunger 65 and moves the same rearwardly from its forward position, the control cable 77 is moved rearwardly by the expansion of spring 93 and contraction of spring 95, thus releasing the control lever 51 and permitting the spring unit 34 to return the drum 13 to its normal, rearward, unlocked position. When the switch plunger 65 and the drum 13 are both in this rearward position, the drum can only be moved forwardly against the spring unit 34 by its inertia when the movement of the vehicle is abruptly decelerated, as hereinbefore described in detail.

The inertia-actuated parts of the reel automatically restrain the chair occupant against forward movement in emergencies in instances when the occupant has adjusted the control switch to permit freedom of movement, and also 75 in instances when the occupant might prefer

safety to freedom of movement but has forgotten to move the control switch to its forward position to thus lock the harness cable.

The invention has been shown applied to the pilot's chair for an airplane, but it may also be applied to airplane passenger chairs, and to driver's and passenger chairs in other vehicles such as motorcars and railroad trains with effectiveness. In general, the invention may find useful application wherever an automatic, inertia-locked reel is required.

While but one specific embodiment of the invention has been herein shown and described, it will be understood that many details of construction may be altered or omitted without departing from the spirit of the invention as the same is defined by the following claims.

I claim:

1. In a device of the class described, a base, a drum rotatably and slidably mounted on the base, a cable connected to said drum and adapted to be wound thereon, means for normally yieldingly urging said drum in a rotating direction for winding the cable thereon, and ratchet means fixedly positioned on the base and the drum adapted to engage when cooperating ratchet means on the drum is slid in one direction relative to the base to thus prevent rotation of the drum in a direction for unwinding the cable and permit rotation of the drum in a direction for winding the cable, said ratchet means being adapted to disengage when the drum is slid in the opposite direction relative to the base.

2. In a device of the class described, a base, a drum rotatably and slidably mounted on the base, a cable connected to said drum and adapted to be wound thereon, means for normally yieldingly urging said drum in a rotating direction for winding the cable thereon, ratchet means fixedly positioned on the base and cooperating ratchet means on the drum adapted to engage the ratchet means on the base when the drum is slid in one direction relative to the base to thus prevent rotation of the drum in a direction for unwinding the cable and permit rotation of the drum in a direction for winding the cable, said ratchet means being adapted to disengage when the drum is slid in the opposite direction relative to the base, and spring means for yieldingly urging the drum to a position disengaging said ratchet means.

3. In a device of the class described, a base, a drum rotatably and slidably mounted on the base, a cable connected to said drum and adapted to be wound thereon, means for normally yieldingly urging said drum in a rotating direction for winding the cable thereon, interlocking ratchets fixedly positioned on the base and cooperating ratchets on the drum adapted to engage the ratchets on the base when the drum is slid in one direction relative to the base to thus prevent rotation of the drum in a direction for unwinding the cable and permit rotation of the drum in a direction for winding the cable, said interlocking ratchets being adapted to disengage when the drum is slid in the opposite direction relative to the base, and spring means for yieldingly urging the drum to a position disengaging said interlocking ratchets.

4. In a device of the class described, a base, a laterally projecting spindle mounted on the base, a drum rotatably and slidably mounted on the spindle, a cable connected to said drum and adapted to be wound thereon, means for normally yieldingly urging said drum in a rotating direction for winding the cable thereon, and ratchet

means fixedly positioned on the base and cooperating ratchet means on the drum adapted to engage the ratchet means on the base when the drum is slid in one direction relative to the base to thus prevent rotation of the drum in a direction for unwinding the cable and permit rotation of the drum in a direction for winding the cable, said ratchet means being adapted to disengage when the drum is slid in the opposite direction relative to the base.

5. In a device of the class described, a base, a drum rotatably and slidably mounted on the base, a cable connected to said drum and adapted to be wound thereon, means for yieldingly urging the drum in a rotating direction for winding the cable thereon, interlocking means on the base and the drum adapted to engage when the drum is slid in one direction relative to the base to thus prevent rotation of the drum in a direction for unwinding the cable, said interlocking means being adapted to disengage when the drum is slid in the opposite direction relative to the base, and a spring unit interposed between the base and the drum for yieldingly urging the drum to a position disengaging said interlocking means, said spring unit comprising complementary spring leaves each stamped to provide a flange at one end, an aperture at the other end and a bowed middle portion, said leaves being secured together in opposite outwardly bowed juxtaposition with the flange on each spring leaf engaging in the aperture on the other spring leaf.

6. In a device of the class described, a base, a laterally projecting spindle mounted on the base, a drum rotatably and slidably mounted on the spindle, a cable connected to said drum and adapted to be wound thereon, a coil spring having its inner end secured to the spindle and its outer end secured to the drum for yieldingly urging said drum in a rotating direction for winding the cable thereon, interlocking ratchets on the base and the drum adapted to engage when the drum is slid in one direction relative to the base to thus prevent rotation of the drum in a direction for unwinding the cable, said interlocking ratchets being adapted to disengage when the drum is slid in the opposite direction relative to the base, a spring unit interposed between the base and the drum for yieldingly urging the drum to a position disengaging said interlocking ratchets, said spring unit comprising complementary spring leaves each stamped to provide a flange at one end, an aperture at the other end and a bowed middle portion having a central opening through which passes the spindle on the base, said leaves being secured together in opposite outwardly bowed juxtaposition with the flange on each spring leaf engaging in the aperture on the other spring leaf.

7. In a device of the class described, a base, a drum rotatably and slidably mounted on the base, a cable connected to said drum and adapted to be wound thereon, means for normally yieldingly urging said drum in a rotating direction for winding the cable thereon, ratchet means on the base and the drum adapted to engage when the drum is slid in one direction relative to the base to thus prevent rotation of the drum in a direction for unwinding the cable and permit rotation of the drum in a direction for winding the cable, said ratchet means being adapted to disengage when the drum is slid in the opposite direction relative to the base, and a manually operable control lever associated with said drum for effecting 75 sliding movement thereof relative to the base.

8. In a device of the class described, a base, a drum rotatably and slidably mounted on the base, a cable connected to said drum and adapted to be wound thereon, means for normally yieldingly urging said drum in a rotating direction for winding the cable thereon, ratchet means on the base and the drum adapted to engage when the drum is slid in one direction relative to the base to thus prevent rotation of the drum in a direction for unwinding the cable and permit rotation of the drum in a direction for winding the cable, said ratchet means being adapted to disengage when the drum is slid in the opposite direction relative to the base, a housing mounted on the base and enclosing said drum, and a manually operable control lever pivotally mounted on the housing and associated with said drum for effecting sliding movement thereof relative to the base.

9. In combination, a vehicle, a chair therein, a harness for the chair occupant associated with the chair, a drum rotatably mounted on the vehicle in association with the chair, a cable connected to the harness and to the drum whereby rotation of the drum in one direction winds the cable thereon to tighten the harness and opposite rotation of the drum unwinds the cable to relax the harness, a locking member on the vehicle and a cooperative locking member on the drum, one of said locking members being fixed relative to the vehicle and the other of said locking members being movable relative to the vehicle and responsive to abrupt deceleration of the vehicle so as to move by inertia into cooperative engagement with the fixed locking member to lock the drum against rotation in the direction which unwinds the cable.

10. In combination, a vehicle, a chair therein, a harness for the chair occupant associated with the chair, a drum mounted in the vehicle for forward-rearward sliding movement relative to the vehicle and for rotation about an axis extending forwardly-rearwardly of the vehicle, a cable connected to the harness and to the drum whereby rotation of the drum in one direction winds the cable thereon to tighten the harness and opposite rotation of the drum unwinds the cable to relax the harness, and locking means fixedly mounted on the vehicle adapted to engage the drum in the latter's forwardly slid position to prevent rotation thereof.

11. In combination, a vehicle, a chair therein, a harness for the chair occupant associated with the chair, a drum mounted in the vehicle for forward-rearward sliding movement relative to the vehicle and for rotation about an axis extending forwardly-rearwardly of the vehicle, a cable connected to the harness and to the drum whereby rotation of the drum in one direction winds the cable thereon to tighten the harness and opposite rotation of the drum unwinds the cable to relax the harness, and locking means fixedly mounted on the vehicle adapted to engage the drum in the latter's forwardly slid position to prevent rotation thereof, said drum being responsive to abrupt deceleration of the vehicle so as to slide by inertia forwardly relative to the vehicle and into engagement with said locking means.

12. In combination, a vehicle, a chair therein, a harness for the chair occupant associated with the chair, a drum mounted in the vehicle for forward-rearward sliding movement relative to the vehicle and for rotation about an axis extending forwardly-rearwardly of the vehicle, a cable con-

nected to the harness and to the drum whereby rotation of the drum in one direction winds the cable thereon to tighten the harness and opposite rotation of the drum unwinds the cable to relax the harness, locking means fixedly mounted on the vehicle adapted to engage the drum in the latter's forwardly slid position to prevent rotation thereof, and spring means for normally urging the drum rearwardly relative to the vehicle.

13. In combination, a vehicle, a chair therein, a harness for the chair occupant associated with the chair, a drum mounted in the vehicle for forward-rearward sliding movement relative to the vehicle and for rotation about an axis extending forwardly-rearwardly of the vehicle, a cable connected to the harness and to the drum whereby rotation of the drum in one direction winds the cable thereon to tighten the harness and opposite rotation of the drum unwinds the cable to relax the harness, locking means fixedly mounted on the vehicle adapted to engage the drum in the latter's forwardly slid position to prevent rotation thereof, and spring means for normally urging the drum rearwardly relative to the vehicle, said spring means being yieldable under forward inertia of the drum to permit the drum to slide forwardly relative to the vehicle and into engagement with said locking means.

14. In a device of the class described, a base, a drum rotatably and slidably mounted on the base, a cable connected to said drum and adapted to be wound thereon, means for normally yieldingly urging said drum in a rotating direction for winding the cable thereon, ratchet means on the base and the drum adapted to engage when the drum is slid in one direction relative to the base to thus prevent rotation of the drum in a direction for unwinding the cable, spring means normally yieldingly urging the drum in an opposite direction to a position of disengagement wherein said drum is rotatable in either direction, manually operable control means associated with the drum for sliding the drum to and maintaining it in its position of engagement, said control means including yieldable spring means permitting limited sliding movement of the drum during its rotating movement in a direction for winding the cable so that the ratchet means on the drum may pass freely over the ratchet means on the base during said winding movement.

Certificate of Correction

Patent No. 2,480,335

August 30, 1949

WALTER E. NORDMARK

It is hereby certified that errors appear in the printed specification of the above numbered patent requiring correction as follows:

Column 5, lines 25, 26 and 27, strike out the words "the drum adapted to engage when cooperating ratchet means on" and insert instead *cooperating ratchet means on the drum adapted to engage the ratchet means on the base when*;

and that the said Letters Patent should be read with these corrections therein that the same may conform to the record of the case in the Patent Office.

Signed and sealed this 14th day of February, A. D. 1950.

[SEAL]

THOMAS F. MURPHY,
Assistant Commissioner of Patents.
